UNITED STATES PATENT OFFICE.

ALBERT L. GOODENOW AND WILLIAM J. OWENS, OF UTICA, NEW YORK.

GRATE.

SPECIFICATION forming part of Letters Patent No. 231,710, dated August 31, 1880.

Application filed July 16, 1880. (Model.)

To all whom it may concern:

Be it known that we, ALBERT L. GOODENOW and WILLIAM J. OWENS, citizens of the United States, residing at Utica, in the county 5 of Oneida and State of New York, have invented certain new and useful Improvements in Grates; and we do hereby declare the following to be a full, clear, and exact description of the invention, such as will enable 10 others skilled in the art to which it appertains to make and use the same, reference being had to the accompanying drawings, and to letters or figures of reference marked thereon, which form a part of this specification.

15 Similar letters indicate like parts.

Our invention relates to an improvement in the class of rotary grates and their connections for stoves and furnaces; and it consists in certain details and principles of construction, 20 hereinafter more fully described and shown.

Its object is to provide a grate that is easily operated, and will effectually and quickly clear the fire of ashes and break up and remove all clinkers, slag, and cinders.

25 In the drawings, Figure 1 is a plan view of our grate and its connections. Fig. 2 is a side elevation. Fig. 3 is the frame or rest upon which the grate is supported and oscillated. Fig. 4 is a section, in detail, of the grate and 30 grate-rest, representing the anti-friction roller beneath the grate and its bearings, also the annular groove or track in the rim of the grate corresponding to the periphery of the roller. Fig. 5 represents one of the horizontal grate-bars through the center of the grate. Fig. 6 is a section through the line $x-x$ of Fig. 2, representing the ash-sifter, its rollers o' , and their 35 bearings $e' d''$.

The grate A is circular in form, and is provided with one or more central horizontal bars, Q, the ends of which are pivoted in opposite sides of the rim of the grate, whereby they are capable of an independent rocking motion. Depending from the front end of these bars 40 are forked arms R, which embrace concentric radial studs S, projecting from the inner side of the grate-ring.

The grate-frame is hinged or pivoted to the rear of the furnace in the usual manner, and a 45 hook or latch, d, is provided in front for holding it in place. At suitable intervals slots N

are provided for the rollers O. The edges of these slots, which form the track or bearings for the rollers, are beveled or A-shaped, in order that they may readily clear of ashes, and 55 corresponding A-shaped grooves are provided in the arbors of the rollers to enable them to fit thereon. The grate rests upon these rollers, their periphery occupying the annular groove P in its outer rim. It is rendered thereby capable of being freely and easily rotated on its vertical axis without regard to the superincumbent weight upon it, while its central horizontal bars, Q, by means of the depending forked arms R, embracing the radial studs S, 60 are caused to rock in unison, and by means of projecting teeth or studs on their surface serve to grind and pulverize all cinders, slag, and clinkers, which ordinarily find their way to the center of the grate and serve to block up and 65 deaden the fire.

a is the shaker—a short lever fulcrumed in front of the grate, its end projecting through its rim between the bars Q.

The ash-sifter B is located below the grate 75 and a little in front of it, and consists of a perforated plate resting upon anti-friction rollers o' , similar to those already described, upon which it has a free horizontal motion, and serves to separate the finer particles of coal 80 which escape through the grate from the ashes.

We are aware that grates have been heretofore constructed having horizontally-pivoted rotating bars. We are also aware that anti-friction wheels or rollers have been employed 85 in connection with grates and furnaces; but we do not claim these, broadly.

What we claim, and desire to secure by Letters Patent, is—

1. The circular grate provided with the central pivoted rocking bars, Q, having the depending forked arms R, in combination with the studs S of the ring or frame, substantially as described, and for the purpose specified. 90

2. The combination of the recessed grate A, 95 the rollers O, mounted in the grate-ring M, having the grooved arbors e, fitting the conical supports d' , with the ash-sifter supported on similar rollers, substantially as described, and for the purpose specified.

3. The combination of the grate A, grate-rest M, having the conical bearings d' , and the 100

rollers O, with the grooved arbors e, substantially as described, and for the purpose specified.

4. The perforated ash-sifter B, mounted on 5 anti-friction rollers o', with grooved arbors e', in combination with the grate and grate-rest, substantially as and for the purpose specified.

5. A grate constructed substantially as herein described, having central pivoted horizontal bars, which are caused to rock when the grate

is oscillated by means of depending forked arms embracing fixed radial studs in the grating, for the purpose set forth.

In testimony whereof we affix our signatures 15 in presence of two witnesses.

ALBERT L. GOODNOW.
WILLIAM J. OWENS.
